(57) **CLAIM**

The ornamental design for a LED light guide element, as shown and described.

DESCRIPTION

FIG. 1 is a schematic perspective view of the LED light guide element showing my new design;

FIG. 2 is an another schematic perspective view thereof;

FIG. 3 is a front view thereof;

FIG. 4 is a back view thereof;

FIG. 5 is a left view thereof;

FIG. 6 is a right view thereof;

FIG. 7 is a top view thereof;

FIG. 8 is a bottom view thereof;

FIG. 9 is a schematic perspective and enlarged view for the marked section 9 illustrated in FIG. 1;

FIG. 10 is a schematic perspective and enlarged view for the marked section 10 illustrated in FIG. 2;

FIG. 11 is a schematic enlarged view for the marked section 11 illustrated in FIG. 3;

FIG. 12 is a schematic side cross-sectional and enlarged view for the marked section 12 illustrated in FIG. 3;

FIG. 13 is a schematic side cross-sectional and enlarged view for the marked section 13 illustrated in FIG. 3;

FIG. 14 is a schematic enlarged view for the marked section 14 illustrated in FIG. 4; and,

FIG. 15 is a schematic enlarged view for the marked section 15 illustrated in FIG. 7.

This patent application is applied for a partial design in USA, so it will be understood that the dash lines presented in the drawings are for illustration only.

The short dot broken lines shown in the drawings depict the environmental structure and form no part of the claimed design.

The dash-dot-dash broken lines shown in the drawings depict the boundary of the claim and form no part of the claimed design.

(Continued)

The regularly spaced oblique broken lines shown in the drawings depict the environmental cross-sectional portions and form no part of the claimed design.
